(57) **CLAIM**

The ornamental design for an optical property demonstrator as shown and described.

DESCRIPTION

FIG. 1 is a front top right perspective view of an optical property demonstrator having a base and an adjustable lens holder;

FIG. 2 is a rear bottom right perspective view thereof;

FIG. 3 is a left side view thereof;

FIG. 4 is a right side view thereof;

FIG. 5 is a rear view thereof;

FIG. 6 is a front view thereof;

FIG. 7 is a top view thereof;

FIG. 8 is a bottom view thereof;

FIG. 9 is a rear top left perspective view thereof, wherein the lens holder is in an alternative position;

FIG. 10 is a rear bottom left perspective view of the optical property demonstrator shown in FIG. 9;

FIG. 11 is a left side view thereof;

FIG. 12 is a right side view thereof;

FIG. 13 is a rear view thereof;

FIG. 14 is a front view thereof;

FIG. 15 is a top view thereof;

FIG. 16 is a bottom view thereof;

FIG. 17 is a rear top left perspective view of the optical property demonstrator, wherein the adjustable lens holder carries a lens;

FIG. 18 is a rear bottom left perspective view thereof;

FIG. 19 is a left side view thereof;

FIG. 20 is a right side view thereof;

FIG. 21 is a rear view thereof;

FIG. 22 is a front view thereof;

FIG. 23 is a top view thereof;

FIG. 24 is a bottom view thereof;

FIG. 25 is a rear top left perspective view thereof, wherein the lens holder is in the alternative position;

FIG. 26 is a rear bottom left perspective view of the optical property demonstrator shown in FIG. 25;

(Continued)

FIG. 27 is a left side view thereof;
FIG. 28 is a right side view thereof;
FIG. 29 is a rear view thereof;
FIG. 30 is a front view thereof;
FIG. 31 is a top view thereof; and,
FIG. 32 is a bottom view thereof.
